UNITED STATES PATENT OFFICE.

WILLIAM A. LORENZ, OF HARTFORD, CONNECTICUT, ASSIGNOR TO THE OTAKA FABRIC COMPANY, OF HARTFORD, CONNECTICUT, A CORPORATION OF CONNECTICUT.

PAPER-CRINKLING MACHINE.

Application filed June 15, 1920. Serial No. 389,078.

This invention relates to machines for crinkling paper.

My pending application No. 346,810, filed December 20, 1919, discloses certain features which are embodied in the present application.

The paper to be crinkled is led around a rotating drum, and is held firmly thereon by the aid of atmospheric pressure. For this purpose, a partial vacuum is created between the paper and the surface of the drum. This is accomplished by the use of a stationary vacuum box placed at the intake side of the rotating drum. This box has an air intake which projects between the incoming paper web and the drum, to partially exhaust the air between the web and the drum, so that atmospheric pressure pinches the web to the drum or cylinder. The leading edge 15 of the web is advanced against a doctor blade and is stripped thereby from the drum, the paper becoming transversely crinkled by the doctor blade. Atmospheric pressure aids in causing the paper to adhere firmly to the drum, thus improving the efficiency of the crinkling device.

Means may be provided for dampening the paper, if desired, upon either one or both sides, preparatory to running it over the drum.

Other features and advantages will herein-after appear.

In the accompanying drawings,

Figure 1 is a plan of one form of a machine embodying the invention.

Figure 2 is a sectional side elevation of the same, taken at about the line 2—2, Figure 1.

Figure 3 is an enlarged partial section at 40 the delivery side of the drum, taken at about the line 3—3 of Figure 1. This view also shows the vacuum-box in cross-section.

The web to be crinkled may be led (preferably in dry condition) from a supply spool 45 10, rotation of which may be retarded or regulated by a brake device comprising an inclined strap 11 suspended from a fixture 12, and pulled down by a weight 13. The web may be led up over a guide roll 14 and 50 down to a drum 15, which is of relatively large diameter, and may be driven by a pulley 16, having a pinion 17 in mesh with a gear 18 fixed to the drum.

To aid in causing the web to cling to the 55 drum and advance therewith, there is pro-

vided means for partially exhausting the air from between the web and drum, so that the web is held against the cylinder by atmospheric pressure. For this purpose, there is preferably employed a stationary 60 vacuum-box or exhauster 19, from which air is drawn through a pipe 20. The vacuum-box is stationary, and is open only upon its under side. This under side may conform to the curvature of the drum, so that the 65 latter, although revolving, may substantially close the box, so as to enable a partial vacuum to be created within the box. The ends of the box are indicated at 21, and the front side at 22. The rear side may be in the form 70 of a doctor blade 23, which is held by bolts 24 upon a flange 25 provided on the box; the whole fitting closely to the surface of the drum, so as to minimize leakage of air into the box, which extends from the introductory 75 side to the delivery side of the drum. The front side of the box is extended at 26 far down into the angle formed by the incoming web with the surface of the rotating drum, a little clearance at 27 being provided between this air-intake end or extension of the 80 box and the surface of the drum, so that air may be drawn into the box from the space between the web and the drum. Hence, exhaustion of air from the box produces a 85 partial vacuum between the web and the drum 15, so that the advancing web is atmospherically pressed at all points against the drum. The vacuum persists between the 90 paper and the drum all the way around the drum. Thus, the atmosphere may maintain a firm control over the web until it is stripped from the cylinder. The pressure exerted by the atmosphere and the force of a feed-roll 31 may be relied upon to urge or 95 force the leading portion of the advancing web edgewise against the stationary doctor blade 23, to enable the latter to strip the web from the cylinder by a crimping action, so that the web is crimped or crinkled as at 29. 100 The crimped paper emerges over the power-driven delivery rolls or belts 30.

The pressure roll 31 at the delivery side of the drum may have a soft rubber face and 105 may be driven either by gearing or by surface contact with the drum or the paper thereon, and may have suitable springs or pressure devices 32 provided with individual regulating means 33. The vacuum which is maintained in the box during the crimping 110

operation may be varied, according to the thickness or quality of the paper to be crimped.

In some cases it is desirable to moisten the paper slightly, and this may be done either by use of steam or by means of atomizer devices, arranged at either side of the web or at both sides. There is illustrated a sprinkling pipe 34 extending along the web upon one side to moisten the same, and a second sprinkling pipe 35 extending across the web on the other side, so that either one or both sides may be moistened.

The speed of the machine may be varied and thereby the crinkling may be modified. Variation in the appearance of the crimping may also be produced by making the face of the doctor blade more or less abrupt.

Variations in the crimping may also be produced by varying the degree of vacuum in the vacuum-box, so as to cause the atmosphere to hold the web more or less closely to the drum or cylinder 15, and urge it with more or less force against the doctor blade, which bears upon the surface of the cylinder. It will not be usually desirable to take the preliminary step of dipping the paper into a saturating water bath, with liability to weaken the paper permanently. The pressure roll 31 may also serve to press out surplus water from the moistened or wet paper, and cause it to adhere smoothly to the surface of the drum.

Variations may be resorted to within the scope of the invention, and portions of the improvements may be used without others.

Having thus described my invention, I claim:

1. The combination of a supply-roll, a

brake therefor, a guide-roll over which a web is led from the supply-roll, a main cylinder, means for exhausting air between the web and the main cylinder, to cause the atmosphere to press the web against the cylinder, said exhausting means comprising a vacuum box having a side which extends into the bight of said cylinder and the web, a doctor blade mounted at the delivery side of said cylinder and forming a part of said vacuum box, a feeding-roll running upon the delivery side of the main cylinder, and having an elastic surface, said doctor blade at an angle, to hold back the advancing paper and crinkle it, and means for dampening the paper on both sides preparatory to advancing it around said main cylinder.

2. The combination of a roll over which the web is laid, a main cylinder, means externally of said cylinder for exhausting the air from between the web and cylinder, a doctor blade mounted at the delivery side of said cylinder, a feeding roll running upon the delivery side of said cylinder, and means for dampening the web preparatory to advancing the same around said main cylinder.

3. Paper crinkling apparatus comprising a crinkling drum over which a web is laid, and means for exhausting air from between the web and the drum, said exhausting means comprising a vacuum box having a side which extends into the bight of the cylinder and the web at the point at which the web is delivered onto the cylinder, said box having a doctor blade cooperating with said cylinder.

WILLIAM A. LORENZ.
